UNITED STATES PATENT OFFICE.

ENOS MITCHELL, OF WELDON, IOWA.

COMBINED SCREEN AND WEATHER DOOR.

SPECIFICATION forming part of Letters Patent No. 507,827, dated October 31, 1893.

Application filed June 23, 1893. Serial No. 478,599. (No model.)

To all whom it may concern:

Be it known that I, ENOS MITCHELL, a citizen of the United States, residing at Weldon, in the county of Decatur and State of Iowa, have invented certain new and useful improvements in a Combined Screen and Weather Door; and I do hereby declare the following to be a full, clear, and exact description of the invention, such as will enable others skilled in the art to which it appertains to make and use the same.

This invention relates to an improvement in a combined screen and weather door and consists in the construction and arrangements of parts hereinafter described and definitely pointed out in the claims.

The object of the invention is to provide an improved screen door which can be readily transformed into a weather door. These objects are attained by the construction illustrated in the accompanying drawings wherein like letters of reference indicate corresponding parts in the several views and in which—

25 Figure 1 is a rear elevation of a door. Fig. 2 is a vertical section. Fig. 3 is a perspective view of the lower section of the door with the detachable connections removed, and Fig. 4 is a detail perspective of the weather strip.

30 In the drawings A represents the door frame on the outer face of which is secured the wire screen B. The lower edge of the door frame has a series of cross grooves b formed in the edge thereof their inner ends extending up through the inner face of the lower cross bar of the door and terminate at the upper edge of said cross bar.

When it is desired to transform the screen door into a storm door I employ a metal panel 40 C the edges of which project beyond the openings in the door frame and are secured by placing thereon suitable moldings D, extending around the entire edge thereof. This molding is secured to the door by suitable bolts d which pass therethrough and through the sides and end bars of the door frame and are capped by suitable nuts d'. The panel and molding are placed on the inner face of the door or opposite the screen which as stated 45 50 is on the outer face of the door.

E is a metallic weather strip consisting of a vertical inner section e an inclined central section e' and a depending outer edge e''. This strip is placed on the base or lower edge of the door frame the central section thereof 55 extending across the lower edge over the grooves while its upper edge e is extending up between the lower molding and lower edge of the panel and is there closely bound and secured to the frame by the bolts d with which 60 the lower molding is attached to the door frame.

By the above described construction it will be seen that when it is desired to place the panel on the door it is only necessary to remove the molding, adjust the panel and weather strip and replace the molding. In placing the panel on the rear face of the door the rain beating through the screen will strike the panel, be conducted down the outer face 65 thereof, enter the grooves b at the base of the door striking the weather strip and be led off from the front edge thereof thereby preventing the same from entering the house. The depending flange on the weather strip 70 75 also prevents the ingress of rain, &c., below the door.

It is evident that minor changes in the construction and arrangements of parts of the device can be made and substituted for those 80 herein shown and described without in the least departing from the nature and principle of my invention.

Having thus described my invention, what I claim as new, and desire to secure by Letters 85 Patent, is—

1. In a combined screen and weather door, the combination with a door frame, of a screen on the outer face thereof, a removable panel on the inner face thereof and a weather strip 90 consisting of a vertical upper end secured to the lower edge of the door and rear face of the panel, a forwardly extending inclined section and a depending forward edge, substantially as described.

2. In a combined screen and weather door, the combination with a door frame having its lower cross bar grooved on its inner face and lower edge, of a screen secured on the outer face of the frame, a weather panel removably 95 100

secured on the rear face of the frame and a weather strip on the frame having a vertical upper edge arranged on the rear face of the panel a forwardly extending inclined section 5 and a depending flange on the forward edge of the inclined section, substantially as described.

In testimony whereof I affix my signature in presence of two witnesses.

ENOS MITCHELL.
